DESIGN FOR A BOTTLE

Fulton W. Smith, Howard Beach, N. Y., assignor to Colgate-Palmolive-Peet Company, Jersey City, N. J., a corporation of Delaware

Application April 26, 1940, Serial No. 91,965

Term of patent 14 years

To all whom it may concern:

Be it known that I, Fulton W. Smith, a citizen of the United States, residing at Howard Beach, in the county of Queens and State of New York,
have invented a new, original, and ornamental Design for a Bottle, of which the following is a specification, reference being had to the accompanying drawing, forming part thereof.

Figure 1 is a top plan view of the bottle showing my new design.

Figure 2 is a side elevational view; and Figure 3 is a similar view at right angles to Figure 2.

I claim:

The ornamental design for a bottle, substantially as shown.

FULTON W. SMITH.
